UNITED STATES PATENT OFFICE.

MORTIMER NORDEN, OF NEW YORK, N. Y., ASSIGNOR TO JOSEPH NORDEN,
OF SAME PLACE.

DESIGN FOR AN ELECTRIC-LIGHT SIGN.

SPECIFICATION forming part of Design No. 29,046, dated July 12, 1898.

Application filed May 16, 1898. Serial No. 680,882. Term of patent 14 years.

To all whom it may concern:

Be it known that I, MORTIMER NORDEN, a citizen of the United States, residing at New York, in the county and State of New York, have invented and produced a new and original Design for an Electric-Light Sign, of which the following is a specification, reference being had to the accompanying drawings, in which—

10 Figure 1 is an elevation illustrating my design, and Fig. 2 is a cross-section of the same.

My design relates to an electric-light sign wherein letters, characters, or figures may be visually shown by electric illumination.

15 The leading feature of my design for an electric-light sign consists in the design of

the monogram groups of straight and wavy rows of lamp-bases.

The design of the sign monogram of lamp-bases comprises the straight rows, whose extremities are represented by *a d*, *d c*, *c b*, *a b*, *e f*, and *g h*, and the intermediate curved or wavy rows, (indicated at *i k l m*.)

What I claim is—

The design for an electric-light sign, substantially as shown and described.

Signed by me this 28th day of February, 1898.

MORTIMER NORDEN.
